UNITED STATES PATENT OFFICE

1,951,005

CARBOY

Martin Andersen, Brighton, N. Y.

Application March 22, 1932, Serial No. 600,483

6 Claims. (Cl. 217—53)

The object of this invention is to provide a new and improved carboy or wooden box that is adapted to hold a large bottle.

Another object of the invention is to make a top in two pieces which together close the top of the box and close in around the neck of the bottle.

Another object of the invention is to engage these two sections of the top with the box with a sliding dovetailed joint.

Another object of the invention is to provide a small box that interlocks with the top of the carboy and covers the neck and mouth of the bottle.

15 Another object of the invention is to build up a box having four sides and a bottom in the ordinary way, the upright corners being filled with triangular corner braces together with cross bars extending diagonally across the bottom of the box and making contact with the bottom of the corner braces.

Another object of the invention is to provide recesses in the ends of the triangular corner braces at the bottom of the box and to provide 25 rubber cushion pads on the diagonal braces on which the bottle can rest.

Another object of the invention is to provide upright sliding posts adapted to make between the triangular corner braces and the bottle, said posts each having a tongue at the bottom adapted to engage the recess in the end of one of the diagonal braces. These posts are provided with rubber plugs which are adapted to engage the sides of the bottle and hold it in place, the upper plug of each post having a stem projecting through on the other side and engaging the groove at the top of the triangular corner brace with a sliding engagement.

These and other objects of the invention will be fully illustrated in the drawings, described in the specification and pointed out in the claims at the end thereof.

In the drawings,

45 Figure 1 is an upright sectional view on the line 1x 1x of Figure 3.

Figure 2 is a section on the line 2x 2x of Figure 3, the sliding posts being omitted from said figure.

50. Figure 3 is a top plan view of the box with the cover in place.

Figure 4 is a top plan view of the box with the cover removed.

Figure 5 is a side elevation of one of the
55 upright sliding posts.

Figure 6 is a vertical section on the line 6x 6x of Figure 5.

Figure 7 is a top plan view of one of the diagonal braces at the bottom of the box.

Figure 8 is a section on the line $8x-8x$ of Figure 7.

Figure 9 is a vertical section on the line 9x-9x of Figures 3 and 4, showing the upper corner of the box and the cover and the locking device for the cover.

Figure 10 is a section on the line $10x - 10x$ of Figure 3.

Figure 11 is a detailed view of one of the triangular corner braces modified.

Figure 12 is a side elevation of a modified form 70 of the sliding posts, adapted to be used with the part shown in Figure 11.

Figure 13 is a detailed view of the locking device shown in Figure 9.

which is used for unlocking the cover of the carboy.

In the drawings, like reference numerals indicate like parts.

In the drawings, reference numeral 1 indicates like parts.

cates the bottom of the box made up of one or more pieces of wood and having the cross bars or feet 2 and 3 on the bottom thereof. A piece of water proof paper 4 and 5 is provided between these feet and the bottom of the box. From the bottom of the box, arises the triangular corner braces 6, 7, 8 and 9. On the bottom of the box are provided the diagonal braces 10 and 11. These diagonal braces are cut away as shown at 12 in Figure 2 so that the middle part of the one will nest in the middle part of the other.

Two sides of the box are made up of the short boards 13, 14, 15 and 16 and are attached to the triangular corner braces 6, 7, 8 and 9 98 on the two sides of the box and the longer boards 17, 18, 19 and 20 are attached to triangular corner braces on the other two sides of the box. At the top, the last two named sides of the box, are filled by boards of double thickness 21, 21 shown at the top of Figure 1. These boards 21 are made with an undercut groove 22 that can be engaged by the tongue 23 formed on the two sections or halves of the top of the box, that can be pushed in from adjacent sides 10 of the box. In this way, these two halves of the top of the box are securely locked to the sides of the box. The two halves of the cover of the box are shown in Figure 3 where they are marked 25 and 26. 1

As stated above, the edges of these cover sections are each formed with a tongue that is adapted to engage with a groove on the top member 21 of the side of the box as shown in Figure 9. These two cover sections 25 and 26 are cut away at the center to form a circular opening 28, one half of such opening being provided in each box cover section. These cover sections 28 are cut away on a bevel on each side of the circular opening to form an undercut groove 29 in which can engage the tongues 30 that are formed on the bottom of the two thick sides of the box cap, 31, see Figure 10. The two sections of the cover, slide toward the center or toward the neck of the bottle when it is in place and when the outer edges come together, they leave an opening surrounding the neck of the bottle. The undercut grooves 29, 29 are adapted to engage a tenon formed on two sides 20 of the cap 31 that interlocks therewith so that when the two sections of the cover are brought together in place, they will interlock with the tenons 30 formed on the two thick sides of the cap 31 and lock it securely in place.

25 In Figures 5 and 6, I have shown the upright sliding posts 32 that are used in connection with the triangular corner braces 6, 7, etc. that are built at each of the upright corners of the box. On the bottom of each of these posts 32 is provided a tongue 33 which is adapted to engage in the recess 34 formed at each end of the corner braces 10 or 11 shown in Figure 4. These braces 10 and 11 are slotted as shown in Figure 7 and are adapted to receive the rubber plugs 35 shown and used therein on which the bottom of the bottle rests. As indicated at 36, the central parts of the corner braces 10 are cut away to receive a similar cut away part of the cross bar 11.

40 As shown in Figure 9, the upright side board 21 is cut away to form a horizontal sliding groove 38 that is adapted to receive the tenon 39 on the edge of the cover. When the cover is in place, an upright locking bolt 40 is provided in each corner post, which bolt engages an opening 41 on the under side of the cover and by which the section of the cover is locked in place. The bolt 40 rests upon a rubber stem 42 provided in the bottom of the opening 43, which rubber stem 42 holds the bolt 40 up. This stem has an expanded base that more than fills the bottom of the hole and grips it and thereby holds the stem 42 and bolt 40 from falling out if the box is turned over. The locking bolt 40 can be pressed down by a pin or a nail compressing the rubber stem 42. This releases the sliding cover 25 so that it can be pulled away from the neck of the bottle, thereby releasing the small box which covers the mouth and neck of the bottle.

65 In Figure 14, I have shown a yoke 45 having two pins 46 and 47 that are adapted to penetrate the holes 48, 48 in the cover section by which both of the locking bolts 40 that lock one of the sliding cover sections 25 and 26, may be released simultaneously, to permit the opening of the cover section.

70 As shown in Figure 2, the triangular corner braces 6, 7, 8 and 9, each have a slot 50 therein at the top which extends about one-third way down the corner brace. As shown in Figures 5 and 6, the sliding posts 32 are provided with rubber plugs having cushions or heads 51 on one side thereof. The upper plug has a stem 52 which goes through the sliding post 32 and

engages with the slot 50 in the triangular corner brace. The lower plug 51 has its stem cut off flush with the surface of the sliding post.

When the wooden box is assembled, the bottle is set in place on the rubber pads 35, 35 and the sliding posts 32 are then pushed down between the triangular corner braces and the bottle with the pads 51, 51 exposed toward the bottle. The stems 52 engage in the grooves 50 and serve to lock the sliding posts 32 securely between the corner braces and the bottle.

80 The two sections 25 and 26 of the top are then partly brought together and the box 31 is then inserted in place over the mouth of the bottle and the two sections of the top are then closed in on each other engaging with the cap and locking it in place as shown in Figure 10, at the same time being locked in place as shown in Figure 9.

90 In Figure 11, I have shown the modified form of the triangular corner posts in which the groove 50A, runs from the top to the bottom of the post and in such case, the plugs 51 and stem 52, are used at both the bottom and the top of the sliding posts 32.

95 It will be seen from the foregoing that there are no nails or other metal parts exposed on the inside of the carboy, where they could be acted on by acid which would eat them or rust them out quickly.

100 It will also be seen that the carboy can be easily inspected and easily taken apart and put together again sufficient for the purpose of all ordinary repairs.

105 I claim:

110 1. In a carboy, the combination of a box having sides, dovetailed grooves cut in two opposite sides of the box near the top thereof, two equal cover sections each having beveled edges adapted to engage with said grooves and adapted to be inserted therein from opposite sides of the box, said cover sections being adapted to meet in the middle of the box, each of said cover sections being cut away on the meeting edges to form a circular opening between them adapted to receive the mouth of the bottle, said cover sections being cut away on opposite sides of the meeting edges to form a dovetailed groove on each side of such circular opening and radial therewith, a rectangular boxlike cap adapted to cover the top of the bottle, said cap having tenons on the bottom of two opposite sides thereof adapted to engage with the dovetail grooves formed in the two cover sections and interlocked therewith and being held thereby.

115 2. In a carboy, the combination of a base, upright triangular corner braces arising from the base, sides of the box fastened to said corner braces, horizontal braces extending diagonally across the bottom of the box engaging with said

120 upright corner braces, said carboy being adapted to hold a bottle, spacing posts adapted to be inserted between the upright triangular corner braces and the bottle, said horizontal braces

125 having a recess at each end thereof, each of said spacing posts having a tongue on the lower end thereof adapted to engage with one of said recesses, cushion plugs provided on said spacing posts adapted to bear against the bottle.

130 3. In a carboy, the combination of a base, upright triangular corner braces arising from the base, sides of the box fastened to said corner braces, horizontal braces extending diagonally across the bottom of the box engaging with said

135 upright corner braces, said carboy being adapted to hold a bottle, spacing posts adapted to be inserted between the upright triangular corner braces and the bottle, said horizontal braces

140 having a recess at each end thereof, each of said spacing posts having a tongue on the lower end thereof adapted to engage with one of said recesses, cushion plugs provided on said spacing posts adapted to bear against the bottle.

145 4. In a carboy, the combination of a base, upright triangular corner braces arising from the base, sides of the box fastened to said corner braces, horizontal braces extending diagonally across the bottom of the box engaging with said

150 upright corner braces, said carboy being adapted

- to hold a bottle, spacing posts adapted to be inserted between the upright triangular corner braces and the bottle, said horizontal braces having a recess at each end thereof, each of said 5 spacing posts having a tongue on the lower end thereof adapted to engage with one of said recesses, cushion plugs provided on said spacing posts adapted to bear against the bottle, a groove in said corner post, a stem on the rear end of 10 one of said cushion plugs adapted to engage in the groove on the corner post.
4. In a carboy, the combination of a box having sides, dovetailed grooves cut in two opposite sides of the box near the top thereof, two equal 15 cover sections each having beveled edges adapted to engage with said grooves and adapted to be inserted therein from opposite sides of the box, said cover sections being adapted to meet in the middle of the box, an upright locking bolt carried in the top of one of the corner posts, means 20 for normally holding it at the top of its movement, an opening in one of the cover sections with which said bolt is adapted to engage to lock the cover section in closed position from 25 below.
5. In a carboy, the combination of a box having sides, dovetailed grooves cut in two opposite sides of the box near the top thereof, two equal cover sections each having beveled edges adapted to engage with said grooves and adapted to be inserted therein from opposite sides of the box, said cover sections being adapted to meet 30

- in the middle of the box, an upright locking bolt carried in the top of one of the corner posts, means for normally holding it at the top of its movement, a large opening in one of the cover sections with which said bolt is adapted to engage to lock the cover section in closed position from below, a small opening above said large opening in said cover section communicating with said bolt through which the bolt can be pushed down to release the cover section.
6. In a carboy, the combination of a box having sides, dovetailed grooves cut in two opposite sides of the box near the top thereof, two equal cover sections each having beveled edges adapted to engage with said grooves and adapted to be inserted therein from opposite sides of the box, said cover sections being adapted to meet in the middle of the box, an upright locking bolt carried in the top of each of the corner posts, means for normally holding said bolts at the top of their movement, large openings in each of the cover sections with which said bolt is adapted to engage to lock the cover section in closed position from below, a small opening above said large opening in the cover section communicating with said bolt through which the bolt can be pushed down to release the cover section, a yoke having two pins thereon adapted to enter two of said holes and push down two of said bolts at a time.
- MARTIN ANDERSEN.
